4 Claims. (Cl. 367—18)

(Granted under Title 35, U.S. Code (1952), sec. 266)

This invention herein described may be manufactured and used by or for the Government of the United States of America for governmental purposes without the payment of any royalties thereon or therefor.

The present invention relates to a current control device and in particular to a current control device utilizing a single transistor for control of currents of from several to less than one microampere.

Mechanical and electrical relays having moveable electrical contact points have been used for control of small currents. However, relays of this type are expensive and bulky and their repetition reliability, when used for control of small currents, is relatively low because of the difficulty in applying constant pressure to the contact points. Transistors have also been used for the control of small currents. However, transistor circuitry has been confined to applications where the current to be controlled was either an integral part of the control current or the control current was balanced out by utilizing symmetrical electrical circuitry. Current dividing control devices for currents of the order of several microamperes have been complex or cumbersome units compared to the currents to be controlled. Such types of control units have consisted of cascaded potentiometers, cascaded rheostats and amplifiers.

The present invention overcomes the aforementioned difficulties and provides a current control method that is effective for currents of from several to less than one microampere. This is accomplished by reverse biasing the emitter, collector and base of a transistor and by employing two diodes. The load circuit is series connected with the emitter and collector of the transistor and one diode and the control circuit is series connected with the emitter and base of the transistor and another diode. The diodes function to limit the operating range of the circuit by preventing reverse current flow in the load and control circuits.

An object of the present invention is to provide a current control device which is simple, lightweight and of inexpensive construction.

Another object is to provide a current control device wherein load currents of the order of from several to less than one microampere are accurately controlled in response to a control signal.

Still another object is to provide a limited current control device utilizing a single reverse biased transistor wherein the load circuit includes the emitter and collector of the transistor and the control circuit includes the emitter and base of the transistor.

A still further object is to provide a limited current control device utilizing a transistor wherein the use of diodes prevents reverse current from flowing in the load and control circuits.

Other objects and many of the attendant advantages of this invention will become readily appreciated as the same becomes better understood by reference to the following detailed description when considered in connection with the accompanying drawings wherein:

FIG. 1 is a schematic diagram of the preferred embodiment of the present invention;

FIG. 2 is a curve showing the relationship between control current and load current for the FIG. 1 device;

FIG. 3 is a schematic diagram of a further embodiment of the present invention;

2

FIG. 4 is a schematic diagram of a still further embodiment of the present invention; and

FIG. 5 is a schematic diagram of a still further embodiment of the present invention.

5 The current control circuit shown in FIG. 1 includes a transistor 11 having an emitter electrode 13, a collector electrode 15 and a base electrode 17. The control circuit is a series circuit including potential source 19, rheostat 21, switch 23, diode 25, emitter 13 and base 17. 10 Potential source 19 is poled in the control circuit with its positive terminal directly coupled to base electrode 17, and its negative terminal coupled to emitter electrode 13 through the other circuit elements, which is opposite to the polarity relationships of a potential source for biasing the base circuit of a transistor in its normal amplifier operation, and which tends to generate current flow through the transistor between its emitter and base in a direction opposite to the direction of input signal current flow therebetween in its normal amplifier operation. 15 The load circuit is a series circuit including potential source 29, load 31, emitter 13, collector 15 and diode 33. Diodes 25 and 33 are forward biased by means of potential sources 19 and 29, respectively. Potential source 29 is poled in the load circuit with its positive terminal coupled to collector 15 through diode 33, and its negative terminal to emitter 13 through load 31, which is the same as the polarity relationship of a potential source for biasing the collector circuit in its normal amplifier operation, and which tends to generate current flow through the transistor between its collector and emitter in a direction opposite to output signal current flow therebetween in its operation as a conventional amplifier. The base 17 of transistor 11 is reverse biased by potential source 19 and emitter 13 and collector 15 are reverse biased by means of potential source 29. Diodes 25 and 33 are of the type having very high back voltage resistance and very low back leakage current. The use of diodes having low back resistance and high back leakage current will not necessarily prevent useful operation of the circuit in some applications where the leakage currents would not be detrimental to the particular load. Diode 33, in the load circuit, provides low resistance to the load current when polarized, as shown, by means of potential source 29. However, when the voltage of potential source 19, at the base of transistor 11, is greater than the voltage of potential source 29, at the collector thereof, diode 33 is reverse biased and prevents current from potential source 19 from entering the load circuit. It can therefore be seen that diode 33 prevents reverse current from entering the load, which is essential for the protection of many load devices, and also provides protection for transistor 11. It has been found that, by employing diodes 25 and 33 and potential sources 19 and 29, with polarities as described, the current in the load circuit may be selectively varied in an essentially linear manner by adjustment of the magnitude of current through the control circuit, as by adjusting the position of the tap of rheostat 21. FIG. 2 shows a line 34 passing through a plot of control current values and corresponding load current values. In this graph the plotted values of current flow represent current flow in the direction of arrow I_{cont} (FIG. 1), which is the direction opposite to the direction of base circuit current flow of a transistor during its operation as a conventional amplifier, and the plotted values of load current represent current flow in the direction of arrow I_{load} , which is the direction opposite to the direction of collector circuit current flow of a transistor during its operation as a conventional amplifier. It can be seen from the graph that diode 33 limits the load current to its minimum value and approximately within its linear region since the load current is prevented from going past zero and in the re-

verse direction. Control circuit diode 25 provides low resistance to the control current when polarized as shown. When the voltage of potential source 19, at the base of transistor 11, is less than the voltage of potential source 29, at the collector thereof, diode 25 is reverse biased and prevents current from potential source 29 from flowing in the control branch and back through the load. From the graph shown in FIG. 2 it can also be seen that diode 25 limits the load current to its maximum value and within its linear region. This maximum current is that current which will pass through the transistor when a potential, of described polarity and in excess of the potential barrier of the transistor and diode in the load circuit, is applied across the emitter and collector, and the base circuit is open. This also serves to protect the load device since further decrease of the positive bias applied to the base of transistor 11 results in no increase of the load current.

It can therefore be seen that the presence of diodes 25 and 33 allows the circuit to operate only within its linear region, prevents reverse current through the load and establishes a maximum forward load current regardless of the potential applied to the base of the transistor 11. The FIG. 1 circuit can function either as a relay, by actuation of switch 23, or as a linear continuous current control device, by closing switch 23 and varying the resistance of rheostat 21.

In FIG. 2 is a curve showing the relationship between control current and load current for the linear region of the device shown in FIG. 1 when operating as a continuous current control device. From this curve it can be seen that the load current is directly proportional to the control current from somewhat less than one microampere to approximately nine microamperes. As previously explained, diode 33 prevents the load current from decreasing past zero and in the reverse direction and diode 25 prevents the load current from increasing beyond a predetermined value.

In FIG. 3 is shown a modified form of the control device shown in FIG. 1 wherein the load circuit includes an A.C. potential source rather than a D.C. potential source. The load circuit comprises a first series loop including A.C. generator 35, load 37, diode 39, and the emitter and collector of transistor 41, and a second series loop including A.C. generator 35, diode 43, the emitter and collector of transistor 45 and load 37. The control circuit includes two separate control loops wherein the first loop includes potential source 47, rheostat 49, switch 51, diode 53 and the emitter and base of transistor 41 and the second loop includes potential source 55, rheostat 57, switch 59, diode 61 and the emitter and base of transistor 45.

The operation of this circuit is as follows. During the positive half cycle of generator 35, as shown, diode 39 provides low current resistance and diode 43 provides high current resistance. Therefore, current flows clockwise in the first series loop and there is no current flow in the second series loop. During the negative half cycle diode 43 is conducting and diode 39 is non-conducting and current flow clockwise in the second series loop and does not flow in the first series loop. Therefore, load 37 receives an A.C. signal the magnitude of which is dependent upon the potential applied to the bases of transistors 41 and 45. Transistors 41 and 45, of the NPN type, are reverse biased as is the PNP transistor of the device shown in FIG. 1. It should be noted that when diodes 39 and 43 are conducting, respectively, the emitters and collectors of transistors 41 and 45 are respectively reversed biased. The function of diodes 39 and 53 and 43 and 61, respectively, are the same as diodes 33 and 25 of the FIG. 1 device.

In FIG. 4 is shown a modification of the FIG. 3 device. The basic difference between the two circuits being that only a single control circuit is utilized for the two A.C. load loops in the FIG. 4 modification. The load circuit comprises a first series loop including A.C. generator 63,

load 65, diodes 66 and 67 and the emitter and collector of transistor 68 and a second series loop including A.C. generator 63, load 65, diodes 69 and 70 and the emitter and collector of transistor 71. The control circuit includes potential source 72, switch 73, rheostat 74, the base and emitter of transistor 68, diodes 67 and 79 and the base and emitter of transistor 71. The control current is isolated from the load by means of diodes 66 and 69. During the positive half cycle of generator 63, current flows through the first load loop and during the negative half cycle it flows through the second load loop resulting in an A.C. load output which is proportional to the control current.

The device shown in FIG. 5 is a modification of the FIG. 1 device. The FIG. 5 device provides separate control and load circuits having sequential cutoffs wherein a first series load loop includes potential source 81, diode 82, the collector and emitter of transistor 83 and load 84 and a second series load loop including potential source 85, diode 86, the collector and emitter of transistor 83 and load 87. The control circuit comprises a first series loop including potential source 88, the base and emitter of transistor 83, diode 89, rheostat 90 and switch 91 and a second series loop including potential source 88, the base and emitter of transistor 83, diode 89, rheostat 92 and switch 93. The operation of this control circuit is as follows: Assuming potential sources 81 and 85 are of the same value and loads 84 and 87 are the same value, then both load loops will have the same operating ranges and cutoff points as previously described with relation to FIGS. 1 and 2. In addition, however, diodes 82 and 86 make it possible to use a single transistor and different potentials for each of potential sources 81 and 85 in order to obtain different operating ranges for each of the loads. The provision of two control loops, one involving rheostat 90 and switch 91, and the other involving rheostat 92 and switch 93, makes it possible to produce three distinct control points or operating conditions. Closing switch 91 provides one operating condition; closing switch 93 provides a second operating condition; and closing both switches 91 and 93, which places the resistances presented by rheostats 90 and 92 in parallel, provides a third operating condition. It is to be understood that additional control and load loops could be added in order to provide a greater range of control.

Obviously many modifications and variations of the present invention are possible in the light of the above teachings. It is therefore to be understood that within the scope of the appended claims the invention may be practiced otherwise than as specifically described.

What is claimed is:

1. A current control device including first and second transistors, an A.C. potential source and a load, a first load circuit including said A.C. potential source, said load, the emitter and collector of said first transistor and a first diode to prevent current flow through the first load circuit in the conventional direction of current flow through said first transistor between its emitter and collector connected in series, a second load circuit including said A.C. potential source, said load, the emitter and collector of said second transistor and a second diode to prevent current flow through said second load circuit in the conventional direction of current flow through said second transistor between the emitter and collector connected in series, a first control circuit including current control means, a first D.C. potential source poled to generate a current flow through said first control circuit in a direction opposite to the conventional direction of current flow through said first transistor between its emitter and base, and the base and emitter of said first transistor connected in series, a second control circuit including current control means, a second D.C. potential source poled to generate a current flow through said second control circuit in a direction opposite to the conventional direction of current flow through said second transistor between the emitter and base, and the base and emitter of said second transistor connected in series, a second control circuit including current control means, a second D.C. potential source poled to generate a current flow through said second control circuit in a direction opposite to the conventional direction of current flow through said second transistor between the emitter and base.

70

emitter and base, and the base and emitter of said second transistor connected in series, whereby the output of said A.C. potential source passes through said first load circuit during one polarity of its cycle and through said second load circuit during the other polarity.

2. The device of claim 1 including a third and fourth diode, series connected in said first and second control circuit, to prevent current flow through said control circuit in the conventional direction of current flow through the associated transistors between its emitter and base.

3. In an electronic-relay circuit of the type employing a transistor and in which a control circuit through the base-emitter internal path of a transistor is adapted to be opened and closed to thereby selectively energize or de-energize a load circuit through the emitter-collector internal path of the transistor, said control circuit having a first non-coterminal section extending between the base of the transistor and the emitter of the transistor, and said load circuit having a second non-coterminal section extending between the collector of the transistor and the emitter of the transistor, said emitter forming a junction point common to the control and load circuits, the improvements, in combination, comprising;

(a) said transistor being of the type having conventional unipolar characteristics in which predetermined conventional directions of current flow are defined for current flow through its base-emitter and emitter-collector internal paths, respectively,

(b) a first potential source having a first predetermined magnitude of potential serially connected in said first non-coterminal section of the control circuit and poled to cause a current to flow in a direction opposite to the conventional direction of flow through the base-emitter internal path, a second potential source having a second predetermined magnitude of potential serially connected in said second non-coterminal section of the load circuit and poled to cause a current to flow in a direction opposite to the conventional direction of flow through the emitter-collector internal path of the transistor, a first blocking diode serially connected in said first non-coterminal section of the control circuit and poled to present an open circuit to flow of current in the conventional direction through the base-emitter internal path to isolate the first non-coterminal section of the control circuit from current bucking effects as the result of load circuit current flow, and a second blocking diode serially connected in said second non-coterminal section of the load circuit and poled to present an open circuit to flow of current in the conventional direction through the emitter-collector internal path to isolate the second non-coterminal section of the load circuit from current bucking effects as the result of load circuit current flow, and

5

10

15

20

30

45

35

40

minate section of the load circuit and pole to present an open circuit to flow of current in the conventional direction through the emitter-collector internal path to isolate the second non-coterminal section of the load circuit from current bucking effects as the result of control circuit current flow, and

(c) said first and second predetermined magnitudes of potential being chosen to cause the transistor to operate in a mode of its operation characterized by operation of the transistor to produce a current through the load circuit having a magnitude within a first range of values approximately between zero and ten microamperes and which magnitude varies substantially linear inverse proportional relationship in response to current through the control circuit having a second range of values approximately between zero and two microamperes,

whereby the energizing of the load circuit by a current having a predetermined fixed magnitude, within said first range, may be reliably controlled by the opening and closing of the control circuit.

4. A circuit in accordance with claim 3, and

(d) selectively adjustable variable resistance means serially connected in said first non-coterminal section of said control circuit for adjusting the magnitude of control circuit current to thereby permit pre-adjustment of the magnitude of load circuit current to a desired value within said first range in accordance with said inverse relationship.
